TORQUE CONTROLLED ENGINE

Stanley M. Udale, Detroit, Mich., assignor to
George M. Holley and Earl Holley

Application May 10, 1940, Serial No. 334,329

2 Claims. (Cl. 123—98)

The object of this invention is to control the throttle opening, the mixture ratio and the spark advance of an airplane engine by means of the torque.

Torque indicating devices are now coming into common use. These torque devices obviously indicate the brake mean effective pressure.

As it is well known, these airplane engines are built to develop their maximum power at certain altitudes, a few miles above the sea level. Means have to be provided, therefore, to protect them from the effect of the dense layer of air found at sea level. It has been found desirable that the throttles be gradually opened as the plane ascends to the ordinary flying elevations. It has also been found desirable to advance the spark as the air density falls, or to put it the other way, to retard the spark slightly when the abnormal heavy air adjacent to the sea level is encountered.

Modern airplane engines are always fitted with a supercharger and with constant speed propellers, and the presence of these devices must be considered in controlling and limiting the maximum torque.

Figure 1 shows diagrammatically an air cooled radial engine having a torque responsive device.

Figure 2 shows the control means for the carburetor and ignition devices controlled by the torque responsive means of Figure 1.

Figure 3 shows the carburetor attached to a conventional engine having a supercharger and a torque control.

Figure 4 shows the end view of the torque control. Neither the engine nor the torque control forms any part of this invention.

The invention is shown diagrammatically in the drawings in which a radial air-cooled engine is shown diagrammatically at 10 on which is mounted a torque responsive device 11, a supercharger 43 and mixture outlet 44. This engine 10 and supercharger 43 are drawn to a small scale whereas the rest of the diagram is drawn on a large scale.

The torque responsive device 11 is connected by the pipe 12 with the cylinder 13 in which reciprocates a piston 14 which constitutes a torque control. The torque indicating device corresponds to one of those described in the S. A. E. Journal for June, 1939, pages 271-276, and specifically to Figure 4, on page 273, and is made sufficiently powerful so that it can operate the piston 14. This piston 14 carries a collar 15 with which engages a pin 16 projecting from a lever 11. This lever 11 is connected by the rod 18 with

the throttle 19. The piston 14 is guided in a cylinder 20 which carries a compression spring 21 so that the pressure in the cylinder 13 is balanced by the compression of the spring 21. The cylinder 20 carries a collar 22 with which engages a pin 23 projecting from the manually controlled lever 24 which is controlled by the manually controlled rod 25. This lever 24 is connected by a one-way connection 41 with the lever 17 and the limit to the opening movement of the lever 24 is determined by the stop 40.

The carburetor is shown diagrammatically having an anterior throttle 19, a fuel and air nozzle 35 having a restricted air entrance 36 and a restricted fuel entrance 45 controlled by a needle valve 46 which in its turn is controlled by aneroid bellows 32. A float 31 in a float chamber 47 subjected to the inlet manifold suction controls the float mechanism which supplies fuel to the constant level chamber 47 in order to add extra fuel when the torque reaches its maximum.

The piston 33 is shown connected by the pipe 37 with the cylinder 13. This piston 33 carries a needle valve 34 which admits the extra fuel to the fuel nozzle 35 when the maximum torque is reached. At the same time, a one way link 39 rotates the timer 30 to retard the spark slightly when maximum torque is recorded. A one way connection 38 enables the engine to be idle, because when the levers 24 and 17 are turned clockwise as far as possible, then the spark is retarded in the well known manner for the obvious purpose of giving a moderately smooth idle. As is well known these engines do not idle in a satisfactory manner in any event, but there is some advantage in retarding the spark. A compression spring 42 maintains the one way connection 39 connected to the timer 30.

In Figure 3, the carburetor is shown connected 40 through pipe 44 with the supercharger 50 contained within the housing 43. This supercharger is driven by a crank shaft 51 connected with a piston 52 which reciprocates in the cylinder 53 having the usual inlet and outlet valves 54 and 55. The spark control rod 38 is shown connected to the circuit breaker plate 30 and the circuit breaker itself is shown driven by the two to one gears 56 and 57. The details of the torque control are copied from page 273 of the June, 1939, number of the S. A. E. Journal, Figure 4, and consist of the following:

An internal gear 58 driven by the crank shaft 51 drives an external gear 59 which is connected to the diamond-shaped piece 60 which is connected through the connecting rods 61 and 62 to

the pistons 63 and 64. A valve 65 admits high pressure oil to the line 66. The pressure in the pipe 67 is thus automatically maintained equal to that of the torque created by the engine. The high pressure oil, the pressure of which varies with the torque, is connected through the pipe 12 to the apparatus shown in Figure 2. The propeller take-off is through the shaft 68 which carries the arm 69 upon which are mounted gears 70, 70, which engage with both the external gear 68 and the internal gear 59. Any torque that may be applied to the propeller on the shaft 68 is transmitted through the shaft 68 to the spider 68 which carries the pinion 70. If the torque goes up, the pressure in the pipe 12 goes up, and vice versa.

Operation

When the manually controlled lever 24 is moved to the left to open the throttle by compressing the spring 21, the engine runs with the throttle 19 wide open until the torque responsive device 11 creates sufficient pressure so as to compress the spring 21 and to close the throttle 19 into the position determined by the stiffness of the spring 21. If the plane is now flown to the ordinary heights for which these engines are designed to operate, the throttle 19 will gradually open in order to maintain a constant torque and this will continue until the throttle 19 is wide open and thereafter the torque will continually fall as the air density falls in a well known manner, until finally the plane can climb no more, because the power is not great enough and the air density is too low to lift the plane.

When the plane reaches the point at which it can no longer maintain its maximum torque, the fuel needle valve 34 shuts off and the timer 20 is retarded slightly so that the plane operates with the cruising lean mixture. When cruising lean

at ordinary levels, say one or two miles, the throttle 19 is closed and the compression of the spring 21 is reduced and the lever 17 finds the position which will develop the desired torque, 5 which torque is reduced slightly as the plane ascends and the spring 21 expands to open the throttle 19. This has the desirable advantage that the maximum power is developed near the sea level and there is a slight drop in power with 10 altitude at all positions of the throttle, assuming that the plane climbs with a fixed throttle. The reverse takes place when constant density is maintained in a supercharger 43. It is preferable that the power should fall slightly rather than rise considerably as the plane is flown to higher altitudes. Excessive power at altitude is 15 of no value.

What I claim is:

1. A torque control for an internal combustion engine having a carburetor, a throttle therefor, 20 a fuel valve therefor, adapted to admit extra fuel to obtain maximum power, an ignition timing device, a torque indicating device, and means responsive to the torque when the torque exceeds a predetermined maximum torque for closing the throttle, for admitting extra fuel and for retarding the timing device.

2. A torque control for an internal combustion engine having a torque indicating device, a carburetor and a throttle therefor, an automatically operated throttle lever, a manually controlled throttle lever, spring means interposed between said levers, and means responsive to the torque for opposing said spring means whereby the manually controlled throttle lever can be set to a given torque and the automatically controlled throttle lever will open and close the throttle so as to maintain the torque constant at various altitudes.

STANLEY M. UDALE.
